UNITED STATES PATENT OFFICE.

CARL CHRISTOPH LUDWIG LUCHT, OF COLBERG, PRUSSIA, GERMANY.

PROPELLING AND STEERING APPARATUS FOR VESSELS.

SPECIFICATION forming part of Letters Patent No. 366,849, dated July 19, 1887.

Application filed January 5, 1886. Serial No. 187,684. (No model.)

To all whom it may concern:

Be it known that I, CARL CHRISTOPH LUDWIG LUCHT, a subject of the King of Prussia, residing at Colberg, in the Kingdom of Prussia, 5 Germany, have invented new and useful Improvements in Propelling and Steering Apparatus for Vessels, Boats, and the Like; and I do declare that the following is a true and accurate description thereof, reference being had to the accompanying drawings, and to the letters of reference marked thereon, and being a part of this specification.

This invention relates to certain new and useful improvements in that class of propelling devices in which pairs of hinged wings are used, which automatically separate when moved in one direction and swing together when moved in the opposite direction.

Reference is to be had to the accompanying 20 drawings, forming a part of this specification, in which similar letters of reference indicate corresponding parts in all the figures.

Figure 1 is a rear view of a vessel provided with my improved propelling device, parts 25 being in section. Fig. 2 is a sectional plan view of the same. Fig. 3 is a side view of the same. Fig. 4 is a plan view. Fig. 5 is an enlarged face view of the propelling device, parts being broken out. Fig. 6 is a plan view of the 30 same, parts being broken out.

The vessel is provided with a steam or air motor of any system, which is not shown. The motor revolves a crank-shaft, A, on the deck, which is connected by the rods B and C with 35 an arm of a disk, D, mounted on the upper end of the shaft E, journaled vertically in the rear part of the vessel. On the lower part of said shaft the arms F are secured, which project from opposite sides of the shaft, and are 40 suitably stiffened and braced. In said arms F the vertical shafts G are journaled, on the end parts of which the arms I are mounted to swing toward and from each other, and in the swinging ends of said arms the shafts K are

45 mounted to turn, and on said shafts the wings or flaps H are mounted, which are connected by hinges at L. As shown in Fig. 6, the two wings or flaps H of the same shaft, G, are in the same plane, and press with their entire

50 surface against the water when the shaft E revolves in the direction of its arrow, Fig. 6. When the said shaft E turns in the inverse di-

rection, the wings are swung together and closed by the back-pressure of the water, the wings turning on their shafts K. When in 55 this position, the wings can pass through the water very easily, as they offer no resistance. In order to avoid the counter-pressure of the water when the wings are swung together, guard-plates M are applied, which are riveted 60 at their upper and lower parts to the arms I. During the backward movement of the wing mechanism the water exerts a pressure only against the outside or exterior halves of the flaps or wings H, and thus the closing of the 65 same is facilitated.

To further facilitate the closing of the wings, a spiral spring or a plate-spring, N, is provided, which presses against the outside halves of the wings, and which is in tension when 70 the wings act against the water. When the pressure against the water ceases, the springs N press the wings H together, and they are then completely folded by the pressure of the water. When the direction of movement of 75 the vessel is to be reversed, the wings H must be reversed, which is accomplished in the following manner: Upon the upper deck the hand-wheel o is mounted, from which the shaft Q, carrying a sprocket-wheel, can be revolved by 80 means of the chain P.

The cog-wheel R on the shaft Q engages with the cog-wheel R' on the shaft S, mounted on the disk D and carrying the two bevel cog-wheels 85 TT' engaging with the bevel cog-wheels T'T' on the two vertical shafts U U, mounted in bearings V V on the shaft E. By means of the cranks W W, Fig. 6, and the rods X X, the motion is transmitted from the shafts U U to the racks Z Z, mounted to slide on the arms 90 F F. Said racks engage with cog-wheels Z' Z' on the shafts G, which wheels are provided with the arms Y Y, which, when the wheels Z' Z' revolve, bear against the arms I I and turn the flaps or wings H one hundred and eighty 95 degrees.

The direction of the vessel can thus be reversed without reversing the engine, and the vessel can be stopped much more rapidly than a vessel provided with paddle-wheels or a 100 screw.

The course of the vessel can also be regulated and controlled from the upper deck.

The hand-wheel o is provided with a pointer,

which shows the inclination of the flaps or wings on a suitable plate.

In order to permit of turning the wings when the vessel is in motion, the teeth of the 5 wheels R and R' are made round, and the contact-point of the two pitch circles of said wheels is on line with the axis of the shaft E.

Having thus described my invention, what I claim as new, and desire to secure by Letters 10 Patent, is—

1. In a mechanism for moving and steering vessels, the combination, with the hinged-together wings mounted on shafts carried by arms supported upon a common shaft arranged 15 on transverse arms connected to a central shaft, of springs arranged to press upon the inner or rear sides of the said hinged-together wings, substantially as and for the purpose set forth.

2. In a mechanism for moving and steering 20 vessels, the combination, with the shafts G, supported in arms F of a shaft, E, and carrying pinions Z, engaging with racks, of the arms I, connected to said shafts G and carrying hinged-together wings H, and mechanism for 25 actuating said racks, substantially as and for the purpose set forth.

3. A mechanism for moving and steering vessels, consisting of wings H, vertically arranged one near the other and hinged two by 30 two, each of which wings turns on a vertical shaft, K, mounted nearly in the center of each wing, and provided on its upper and lower ends with fixed arms I, the arms of one pair of wings being loosely mounted on a common 35 vertical shaft, G, supported by horizontal transverse arms F, which are mounted on a vertical shaft, E, placed between the stern-post and rudder-post, and which arms F have a rocking motion on the said shaft E, the pairs

of wings pressing with their whole surface 40 against the water when they move in a direction opposite to that of the vessel, while when moving in the same direction as the vessel they clap together and offer a decreased resistance to the water, substantially as set forth. 45

4. A mechanism for moving and steering vessels, consisting of transverse arms, in combination with toothed wheels provided with rounded teeth and connected to a rocking shaft, the disposition of said wheels being 50 so as to form an angle with each other, while at the same time being rotatable around their shafts, said shafts being journaled in such manner that the point of intersection of the toothed wheels falls within the axis of the 55 shaft, and the driving-wheel is fixedly journaled, while the driving-wheel is supported by bearings on the shaft and rotates therewith, substantially as herein shown and described.

5. In a mechanism for propelling vessels, 60 the combination, with a vertical shaft, of transverse arms on the same projecting from both sides of the shaft; vertical shafts mounted to turn in the arms, the shafts G on the said arms, arms I on the shafts G, the wings H, mounted 65 on shafts held in the arms I, the toothed wheel Z', turning on the shafts G, the rack Z, guided on the arms in which the shafts G are mounted and engaged with the wheels Z', the rods X, the cranks W, and the shafts U, substantially 70 as herein shown and described.

In testimony whereof I have signed my name to this specification in the presence of two subscribing witnesses.

CARL CHRISTOPH LUDWIG LUCHT.
